UNITED STATES PATENT OFFICE.

HENRY D'OLIER, JR., OF PHILADELPHIA, PENNSYLVANIA

DESIGN FOR AN ELECTRIC-LAMP SHADE.

SPECIFICATION forming part of Design No. 37,246, dated November 22, 1904.

Application filed October 6, 1904. Serial No. 227,483. Term of patent 7 years.

To all whom it may concern:

Be it known that I, HENRY D'OLIER, Jr., a citizen of the United States, residing at Philadelphia, county of Philadelphia and State of Pennsylvania, have invented a new, original, and ornamental Design for an Electric-Lamp Shade, of which the following is a specification, reference being had to the accompanying drawing, forming part thereof.

5 The figure is a perspective view of an electric-lamp shade, showing my new design.

What I claim as new, and desire to secure by Letters Patent, is—

The ornamental design for an electric-lamp shade, as shown.
